(57) **CLAIM**

The ornamental design for an electrical control system enclosure, as shown and described.

DESCRIPTION

FIG. 1 is a top, first side, isometric view of an electrical control system enclosure of my new design;

FIG. 2 is a bottom, second side, isometric view thereof;

FIG. 3 is a top plan view thereof;

FIG. 4 is a front elevation view thereof;

FIG. 5 is a bottom plan view thereof;

FIG. 6 is a rear elevation view thereof;

FIG. 7 is a first side elevation view thereof;

FIG. 8 is a second side elevation view thereof;

FIG. 9 is a top, first side, isometric view of the electrical control system enclosure shown attached to unclaimed components to illustrate a potential environment;

FIG. 10 is a top, second side, isometric, exploded view of the electrical control system enclosure shown with unclaimed components to illustrate a potential environment;

FIG. 11 is a top, first side, isometric view of the electrical control system enclosure shown attached to unclaimed components to illustrate a potential environment;

FIG. 12 is a top, second side, isometric, exploded view of the electrical control system enclosure shown with unclaimed components to illustrate a potential environment; and,
FIG. 13 is a top, first side, isometric view of the electrical control system enclosure shown attached to unclaimed components to illustrate a potential environment.

The electrical control system enclosure is shown with symbolic breaks in its length and width. The appearance of any portion of the article between the break lines forms no part of the claimed design.

The broken lines showing connectors, brackets, and other structure in the drawings represent environmental structure and form no part of the claimed design.

1 Claim, 13 Drawing Sheets
